(57) **CLAIM**

The ornamental design for an electronic document reader, as shown and described.

DESCRIPTION

FIG. 1 is a front side, right side, and bottom side perspective view of the electronic document reader of the present design; FIG. 2 is a rear side, left side, and bottom side perspective view of an embodiment of the electronic document reader of FIG. 1;

FIG. 3 is a front side elevational view of the electronic document reader of FIG. 1;

FIG. 4 is a rear side elevational view of the electronic document reader of FIG. 1;

FIG. 5 is a right side elevational view of the electronic document reader of FIG. 1;

FIG. 6 is a bottom plan view of the electronic document reader of FIG. 1; and,

FIG. 7 is a top plan view of the electronic document reader of FIG. 1.
